UNITED STATES PATENT OFFICE.

DANIEL W. HEYLMAN, OF OSHKOSH, WISCONSIN, ASSIGNOR OF ONE-HALF TO OTTO C. SCHOENFELD, OF OSHKOSH, WISCONSIN.

SASH-ADJUSTER.

1,303,794.

Specification of Letters Patent. Patented May 13, 1919.

Application filed December 10, 1917. Serial No. 206,478.

To all whom it may concern:

Be it known that I, DANIEL W. HEYLMAN, a citizen of the United States, residing at Oshkosh, in the county of Winnebago and 5 State of Wisconsin, have invented certain new and useful Improvements in Sash-Adjusters; and I do declare the following to be a full, clear, and exact description of the invention, such as will enable others skilled in 10 the art to which it appertains to make and use the same.

My invention has for its object to provide a comparatively simple and inexpensive, yet a highly efficient and durable adjuster for storm sashes and the like which may readily be detached during the warmer months, provision being made whereby little obstruction to compact storing of the sashes is caused. 15 With the foregoing general object in view, the invention resides in the novel features of construction and unique combinations of parts to be hereinafter fully described and claimed, the descriptive matter being supplemented by the accompanying drawings 20 which form a part of this specification and in which:

Figure 1 is a vertical section of a window and the storm sash thereof, showing the application of the invention;

Fig. 2 is a horizontal section on the plane of the line 2—2 of Fig. 1 showing the device extended;

Fig. 3 is a similar view but illustrating the adjuster in retracted position;

Figs. 4, 5 and 6 are detail vertical sections on the planes indicated by the lines 4—4, 5—5 and 6—6 respectively of Fig. 2;

Fig. 7 is a detail vertical section on the plane designated by the line 7—7 of Fig. 6;

Fig. 8 is a horizontal section on the plane of the line 8—8 of Fig. 6;

Fig. 9 is a perspective view of one of the toggle links; and

Fig. 10 is a perspective showing the support for one end of the toggle link structure.

In the drawings above briefly described, the numeral 1 designates an outer pair of toggle links, while 2 has reference to an inner pair of such links, the two sets of links being pivoted together at 3 to form an extensible and retractable frame. The ends of the links 2 opposite the pivots 3, are connected by a vertical pivot 4 which also pivots 55 them to an arched support 5 whose arms 6

engage the arms 7 of a U-shaped attaching bracket 8 adapted to be secured to the window sill or to any other appropriate part of the frame. A pivot pin 9, preferably in the form of a screw, connects the arms 6 and 7 60 as shown most clearly in Figs. 4 and 5, this pin serving to permit the necessary angling of the bracket 8, according to the inclination of the window sill, and also acting to permit swinging of the support 5 as the device 65 is adjusted. The screw 9 also serves as a detachable connection between the bracket and the support 5 when removing the adjuster.

The inner ends of the links 2 cross each other and are extended a suitable distance beyond the pivot 4, one of said ends being increased in width and provided with an arcuate slot 10 which is concentric with said pivot. A clamping plate 11 is mounted at 70 one end on the pivot 4 and contacts with the side of said widened end, opposite that engaged by the other link 2, and a clamping bolt 12 rises from the extended end of the last named link through said slot 10 and 80 through the clamping plate 11, said bolt having a wing nut 13. By loosening this nut, the adjuster may be extended as shown in Fig. 2 or retracted as depicted in Fig. 3 and tightening of the nut will hold the device in adjusted position. 85

The outer ends of the toggle links 1 are received between the upper and lower ears 14 of a substantially U shaped supporting member 15 and a vertical pivot 16 is passed 90 through said ears and links as shown clearly in the several figures. The pivot 16 also passes through a hook 17 which is provided for securing the adjuster in retracted position as shown in Fig. 3, said hook engaging 95 a head 4^a formed on the upper end of the pivot 4.

The supporting member 15 passes through an opening 18 in the outwardly stamped central portion 19 of an attaching plate 20 100 which is secured to the sash, and said supporting member is provided with oppositely extending lugs 21 which are received in the shallow socket formed by stamping the plate 20 as described. The edge wall of the opening 18 is formed with a notch 22 and when the entire adjuster is turned a quarter of a revolution, after first removing the pivot pin 9, this notch permits removal of the lugs 21, so that the entire adjuster may be 110

quickly and easily detached from the sash S. It will be observed that the lugs 21 which are featured in Figs. 6, 7, 8 and 10, are received rather loosely in the shallow 5 socket above referred to; these lugs therefore not only affording a quickly detachable connection between the adjuster and the sash, but serving as pivots to permit the angle between the sash and the adjuster to 10 vary as the former is swung inwardly and outwardly. During this movement, the pivot pin 9 also comes into play as above suggested.

The device as a whole is simple and inexpensive, yet is highly efficient and durable. When in use, the wing nut 13 and the bolt 12 will hold the device in any of its numerous adjusted positions and when entirely closed, the hook 17 is used as a positive lock. During the warmer months, when the storm sash is removed, the adjuster may easily be detached by removal of the screw 9, it being then only necessary to turn the device a suitable distance to permit disengagement of the support 15 from the attaching plate 20.

Particular emphasis is laid upon the fact that this plate is substantially flat. This is highly advantageous, since the plate does not therefore furnish any noticeable obstruction to compact storing of the sashes. The bracket 8 may remain upon the window sill or may be detached and again connected to the support 5 by means of the screw 9. 35 In either case, a plurality of separated parts do not exist and thus danger of loss is prevented.

Since probably the best results are obtained from the several specific details shown and described, these details are preferably employed, but I wish it understood that within the scope of the invention as claimed, numerous minor changes may well be made.

45 I claim:

1. A sash adjuster comprising an extensible member and means for connecting one end thereof detachably to the window frame, a supporting member to which the other end 50 of said extensible member is connected, said

supporting member having lateral lugs extending transversely of said member and projecting oppositely from the longitudinal center line thereof, an attaching plate in a plane transverse to the aforementioned center line and adapted to be secured to the sash, said plate having an outwardly bulged body portion forming a shallow socket at the reverse side of the plate, said portion being formed with an opening and a notch 60 in the edge of said opening, said supporting member passing through said opening and having its lugs received in said shallow socket, said notch permitting removal of said supporting member when said extensible member is turned transversely sufficiently to permit withdrawal of one of said lugs through said notch.

2. A sash adjuster comprising a toggle link structure and means for connecting one end thereof detachably to the window frame, a supporting member to which the other end of said link structure is connected, said supporting member having lateral lugs extending transversely of the toggle link structure and projecting oppositely from the longitudinal center line of said structure, an attaching plate in a plane transverse to the plane of said toggle link structure and adapted to be secured to the sash, said plate having an outwardly bulged body portion forming a shallow socket at the reverse side of the plate, said portion being formed with an opening and a notch in the edge of said opening, said supporting member passing through said opening and said lugs being received in said shallow socket, said notch permitting removal of said supporting member when the toggle link structure is turned transversely sufficiently to permit withdrawal of one of said lugs through said notch.

In testimony whereof I have hereunto set my hand in the presence of two subscribing witnesses.

DANIEL W. HEYLMAN.
